REFRIGERATION

Carl Georg Munters, Stockholm, Sweden, assignor to Electrolux Servel Corporation, New York, N. Y., a corporation of Delaware

Application December 13, 1929, Serial No. 413,706
In Germany May 3, 1929

30 Claims. (Cl. 62—118)

My invention relates to the art of refrigeration and particularly to refrigerating apparatus of the absorption type and still more particularly to absorption refrigerating apparatus which operates periodically.

One of the objects of my invention is to prevent vaporous refrigerant which may pass uncondensed through the condenser from entering the evaporator. I propose to accomplish this result by utilizing a fluid which will allow the passage of liquid refrigerant to the evaporator, but which will prevent the passage of vaporized refrigerant. This fluid may be a gas or a liquid having a different specific gravity than that of the refrigerant.

Further objects and advantages of my invention will be apparent from the following description taken in connection with the accompanying drawing which forms a part of this specification and on which:

Fig. 1 is an elevational cross-sectional view of one embodiment of my invention; and

Fig. 2 is an elevational cross-sectional view of another embodiment of the invention.

Referring specially to Fig. 1, reference character 10 designates a generator-absorber which is arranged to be heated by any suitable means such as a gas burner 11. The interior of generator-absorber 10 is divided into a plurality of compartments by means of members 12 through which are formed apertures 13 which allow communication between the different compartments. A conduit 14 is placed in heat exchange relationship with the outside of the generator-absorber 35 and is intended to carry cooling water. Insulating material 15 preferably encloses substantially all of the generator-absorber.

A conduit 16 communicates with the upper part of generator-absorber 10 and passes within 40 an outer conduit 17 and thence communicates with the upper part of a collecting vessel 18. Conduit 17 is supplied with cooling water through a conduit 19 and the combination of conduits 16 and 17 forms a condenser. Conduits 45 14 and 19 are connected to a two-way valve 20 which is supplied with cooling water through a conduit 21. In one position of valve 20 water will flow from conduit 21 to conduit 14 while in the other position all the water will flow from conduit 21 to conduit 19.

The bottom of collecting vessel 18 is in open communication with an evaporator 22 by means of a tubular member 23. Member 23 extends 55 through the insulated wall 24 of a suitable re-

frigerator cabinet so that evaporator 22 is within the cabinet while vessel 18 is on the outside.

The operation of the apparatus is as follows:

The compartments of generator-absorber 10 are filled with a suitable absorbing agent which 60 is preferably in solid form and may consist of carbon or siliceous marl or the like. This absorbing agent has the property of absorbing large volumes of certain gases, for instance ammonia. Upon the application of heat to the generator-absorber, ammonia vapor is expelled from the absorbing agent and passes through conduit 65 16 where most of it is condensed within that portion of the conduit which is within cooling water conduit 17. However, particularly when 70 the heating is first started and the pressure in the unit is low, some refrigerant vapor may pass uncondensed through the condenser and, if there is nothing to prevent it, would pass directly to the evaporator where it would condense due to the 75 lower temperature in the evaporator than in the condenser and thus heat up the evaporator. In order to prevent passage of vaporous refrigerant to the evaporator a quantity of liquid having a less specific weight than and substantially insoluble in the refrigerant is contained within vessel 18, evaporator 22, and member 23.

Refrigerant liquefied in the condenser enters the upper part of vessel 18 and, having a greater specific gravity than the liquid contained therein, passes downwardly through this liquid and displaces the same from the evaporator. However, any vapor entering vessel 18 will be prevented from passing to the evaporator by the liquid in the vessel.

The heating of generator-absorber 10 is continued until such time as a proper quantity of refrigerant has been driven therefrom, which quantity should substantially fill evaporator 22. Thereupon the heat supplied to the generator-absorber is interrupted and valve 20 is shifted to its other position so that cooling water will pass through conduit 14 instead of 19. This will cause a rapid cooling of the generator-absorber which will in turn increase the capacity of the absorbing agent therein to absorb vaporous refrigerant. The vaporous refrigerant in the upper part of the generator-absorber and in conduit 16 will thus be absorbed, which will reduce the pressure existing in the system. This reduced pressure acting 100 on the liquid refrigerant in evaporator 22 will cause this refrigerant to boil and thus absorb heat from the interior of the refrigerator cabinet. The vapor resulting from this boiling will pass upwardly through the insoluble liquid in the 110

upper part of evaporator 22, member 23 and vessel 18 and through conduit 16 back to the generator-absorber where it will be absorbed. When substantially all of the refrigerant has evaporated in 5 evaporator 22 and has been absorbed, valve 20 is reversed and heat again applied to the generator-absorber and the cycle of operation just described is repeated.

Valve 20 and burner 11 are here shown as being 10 manually operable, but any one of several means well known in the art may be employed to automatically control both of these members.

In Fig. 2 is shown a modified form of my invention wherein a gas, inert with respect to the refrigerant, is employed to prevent condensation of refrigerant vapor in the evaporator. Generator-absorber 10 is substantially the same as that shown in Fig. 1 with the exception that the solid absorbing medium is contained in only every 15 other compartment. Conduit 16 leads from the upper part of generator-absorber and passes through a water jacket 17 and communicates directly with the upper part of evaporator 22, the collecting vessel 18 of Fig. 1 being omitted. Cooling water conduit 14 connected with two-way 20 valve 20 is placed in heat exchange relation with the generator-absorber as in Fig. 1.

In this modification every other compartment of the generator-absorber is preferably filled with 30 carbon or calcium chloride or a mixture of the two. These absorbing agents will absorb a large quantity of ammonia which is here used as a refrigerant. Hydrogen is preferably used as the gas which prevents the condensation of ammonia in 35 the evaporator.

Before generator-absorber 10 is heated, practically all the ammonia will be absorbed in the absorbing agent and the remainder of the space therein as well as evaporator 22 will be filled with 40 hydrogen. Upon the application of heat to the generator-absorber, ammonia will be expelled therefrom and will pass with the hydrogen through conduit 16. A portion of the ammonia will pass through conduit 16 without being condensed, due to the low pressure existing in the 45 system when heating is first started. The pressure in the unit will rapidly rise and the hydrogen in evaporator 22 will be compressed. This increased pressure will facilitate the condensation of refrigerant in the condenser, but the large proportion of hydrogen present in the evaporator will maintain the partial pressure of refrigerant vapors therein at so low a value that they will not condense therein. Refrigerant liquefied in 50 the condenser will flow into evaporator 22.

When a sufficient quantity of refrigerant has been expelled from the generator-absorber, the heating will be stopped and the flow of cooling water changed from conduit 17 to conduit 14. The generator-absorber will thus be cooled and 60 the absorbing agent therein will begin to reabsorb the refrigerant. This will result in a reduction of pressure throughout the unit and the liquid refrigerant in evaporator 22 will evaporate.

While I have described two more or less specific 65 embodiments of my invention it is to be understood that modifications thereof fall within its scope. Any automatic means may be employed to regulate the heating and cooling and may be applied to either of the embodiments. Also, other absorbing agents, refrigerants and other 70 combinations of absorbing agents, refrigerants or auxiliary agents may be employed and are intended to be included within the scope of this invention which is to be limited only by the ap-

pended claims construed in the light of the prior art.

As herein used, the term "absorb" is used generically and includes "adsorb". As an example of liquid absorbent, sulphuric acid may be used with water as the refrigerant. 80

What I claim is:

1. That improvement in the art of refrigeration which comprises vaporizing a refrigerant, reducing the temperature of the vaporized refrigerant to liquefy it, passing the liquefied refrigerant to an evaporator, preventing the passage of vaporous refrigerant to the evaporator by utilizing a liquid in which the refrigerant is substantially insoluble and evaporating the liquefied refrigerant in the evaporator. 84

2. That improvement in the art of refrigeration which comprises vaporizing a refrigerant, reducing the temperature of the vaporized refrigerant to liquefy it, passing the liquefied refrigerant to an evaporator, preventing the passage of vaporous refrigerant to the evaporator by utilizing a liquid of less specific gravity than the liquid refrigerant and evaporating the liquid refrigerant in the evaporator. 9

3. That improvement in the art of refrigeration which comprises vaporizing a refrigerant, reducing the temperature of the vaporized refrigerant to liquefy it, passing the liquefied refrigerant to an evaporator, preventing the passage of vaporous refrigerant to the evaporator by utilizing a liquid of less specific gravity than the refrigerant, and in which the refrigerant is substantially insoluble and evaporating the liquid refrigerant in the evaporator. 10

4. That improvement in the art of refrigeration which comprises heating an absorbent to liberate refrigerant vapor therefrom, passing the refrigerant vapor through a region of lowered temperature in order to liquefy it, passing the liquefied refrigerant downwardly through a liquid substantially insoluble in the refrigerant and evaporating the liquefied refrigerant. 11

5. That improvement in the art of refrigeration which comprises heating an absorbent to liberate refrigerant vapor therefrom, passing the refrigerant vapor through a region of lowered temperature in order to liquefy it, passing the liquefied refrigerant through a liquid of less specific gravity than the liquid refrigerant and evaporating the liquefied refrigerant. 1

6. That improvement in the art of refrigeration which comprises heating an absorbent to liberate refrigerant vapor therefrom, passing the refrigerant vapor through a region of lowered temperature in order to liquefy it, passing the liquefied refrigerant through a liquid of less specific gravity than the refrigerant and in which the refrigerant is substantially insoluble and evaporating the liquefied refrigerant. 1

7. That improvement in the art of refrigeration which comprises periodically vaporizing a refrigerant, reducing the temperature of the vaporized refrigerant to liquefy it, passing the liquefied refrigerant to an evaporator, preventing the passage of vaporous refrigerant to the evaporator by utilizing a body of dissimilar liquid, evaporating refrigerant in the evaporator to produce refrigeration and passing the vaporized refrigerant back through said body of liquid. 1

8. That improvement in the art of refrigeration which comprises heating a solution to expel a refrigerant vapor therefrom, reducing the temperature of said vapor to liquefy it, passing the liquefied refrigerant to an evaporator, prevent-

- ing the passage of vaporous refrigerant to the evaporator by utilizing a body of liquid in which the refrigerant is substantially insoluble, reducing the temperature of said solution, absorbing refrigerant vapor due to said reduced temperature and evaporating liquid refrigerant due to reduced pressure resulting from said absorption. 5
9. That improvement in the art of refrigeration which comprises heating a solution to expel a refrigerant vapor therefrom, reducing the temperature of said vapor in order to liquefy it, passing the liquefied refrigerant to an evaporator, preventing the condensation of vaporous refrigerant in the evaporator by utilizing a fluid which 10 is substantially insoluble with respect to the refrigerant, reducing the temperature and pressure of said solution, absorbing refrigerant vapor due to said reduced temperature and evaporating liquid refrigerant due to reduced pressure resulting from said absorption. 15
10. A refrigerating apparatus comprising a generator-absorber containing an absorbent in which a refrigerant is absorbed, a condenser, an evaporator, a collecting vessel above said evaporator and a body of liquid in said evaporator and collecting vessel, said refrigerant being substantially insoluble in said liquid. 20
11. A refrigerating apparatus comprising a generator-absorber containing an absorbent in which a refrigerant is absorbed, a condenser, an evaporator, a collecting vessel above said evaporator and a body of liquid in said evaporator and collecting vessel, said refrigerant having a greater specific gravity than said liquid. 25
- 35 12. A refrigerating apparatus comprising a generator-absorber containing an absorbent in which a refrigerant is absorbed, a condenser, an evaporator, a collecting vessel above said evaporator and a body of liquid in said evaporator and collecting vessel, said refrigerant having a greater specific gravity, than, and being substantially insoluble in, said liquid.
- 40 13. That improvement in the art of refrigeration which comprises heating an absorbent in which refrigerant is absorbed to liberate refrigerant vapor therefrom, reducing the temperature of said vapor to liquefy it, passing the liquefied refrigerant to an evaporator, preventing the condensation of vaporous refrigerant in the evaporator by interposing a fluid which is substantially insoluble with respect to said refrigerant in the path of flow of the refrigerant to the evaporator and evaporating said refrigerant in the evaporator. 45
- 55 14. That improvement in the art of refrigeration which comprises heating an absorbent in which refrigerant is absorbed to liberate refrigerant vapor therefrom, reducing the temperature of said vapor to liquefy it, passing the liquefied refrigerant to an evaporator, preventing the condensation of vaporous refrigerant in the evaporator by interposing a fluid of less specific gravity than the liquid refrigerant in the path of flow of the refrigerant to the evaporator and evaporating said liquid refrigerant in the evaporator. 60
- 65 15. That improvement in the art of refrigeration which comprises heating an absorbent in which refrigerant is absorbed to liberate refrigerant vapor therefrom, reducing the temperature of said vapor to liquefy it, passing the liquefied refrigerant to an evaporator, preventing the condensation of vaporous refrigerant in the evaporator by interposing a fluid of less specific gravity than, and which is substantially insoluble with 70 respect to, the liquid refrigerant in the path of flow of the refrigerant to the evaporator and evaporating said liquid refrigerant in the evaporator. 75
16. That improvement in the art of refrigeration which comprises periodically vaporizing a refrigerant, reducing the temperature of the vaporized refrigerant to liquefy it, passing the liquefied refrigerant to an evaporator, preventing the passage of vaporous refrigerant to the evaporator by utilizing a body of liquid having a lower specific gravity than said liquefied refrigerant in the path of flow of the refrigerant to the evaporator, evaporating refrigerant in the evaporator to produce refrigeration and passing the vaporized refrigerant out of the evaporator through said body of liquid. 80
17. That improvement in the art of refrigeration which comprises periodically vaporizing a refrigerant, reducing the temperature of the vaporized refrigerant to liquefy it, passing the liquefied refrigerant to an evaporator, preventing the passage of vaporous refrigerant to the evaporator by interposing a body of liquid in which the refrigerant is substantially insoluble in the path of flow of the refrigerant to the evaporator, evaporating refrigerant in the evaporator to produce refrigeration and passing the vaporized refrigerant out of the evaporator through said body of liquid. 85
18. That improvement in the art of refrigeration which comprises periodically vaporizing a refrigerant, reducing the temperature of the vaporized refrigerant to liquefy it, passing the liquefied refrigerant to an evaporator, preventing the passage of vaporous refrigerant to the evaporator by interposing a body of liquid having a lower specific gravity than said liquefied refrigerant and in which the refrigerant is substantially insoluble in the path of flow of the refrigerant to the evaporator, evaporating refrigerant in the evaporator to produce refrigeration and passing the vaporized refrigerant out of the evaporator through said body of liquid. 90
19. That improvement in the art of refrigeration which comprises heating an absorbent having refrigerant absorbed therein to expel refrigerant vapor therefrom, reducing the temperature of said vapor to liquefy it, passing the liquefied refrigerant to an evaporator, preventing the passage of vaporous refrigerant to the evaporator by interposing a body of liquid having a lower specific gravity than said liquefied refrigerant in the path of flow of the refrigerant to the evaporator, reducing the temperature of said solution, absorbing refrigerant vapor due to said reduced temperature and evaporating liquid refrigerant due to reduced pressure resulting from said absorption. 105
20. That improvement in the art of refrigeration which comprises heating an absorbent having refrigerant absorbed therein to expel refrigerant vapor therefrom, reducing the temperature of said vapor to liquefy it, passing the liquefied refrigerant to an evaporator, preventing the passage of vaporous refrigerant to the evaporator by interposing a body of liquid having a lower specific gravity than said liquefied refrigerant and in which the refrigerant is substantially insoluble in the path of flow of the refrigerant to the evaporator, reducing the temperature of said solution, absorbing refrigerant vapor due to said reduced temperature and evaporating liquid refrigerant due to reduced pressure resulting from said absorption. 110

- 130
- 135
- 140
- 145
- 150

21. That improvement in the art of refrigeration which comprises heating an absorbent having refrigerant absorbed therein to expel refrigerant vapor therefrom, reducing the temperature of said vapor in order to liquefy it, passing the liquefied refrigerant to an evaporator, preventing the condensation of vaporous refrigerant in said evaporator by utilizing a fluid having a lower specific gravity than said liquefied refrigerant, reducing the temperature and pressure of said solution, absorbing refrigerant vapor due to said reduced temperature and evaporating liquid refrigerant due to reduced pressure resulting from said absorption. 80
- 15 22. That improvement in the art of refrigeration which comprises heating an absorbent having refrigerant absorbed therein to expel refrigerant vapor therefrom, reducing the temperature of said vapor in order to liquefy it, passing the liquefied refrigerant to an evaporator, preventing the condensation of vaporous refrigerant in said evaporator by utilizing a fluid having a lower specific gravity than said liquefied refrigerant and in which the refrigerant is substantially insoluble, reducing the temperature and pressure of said solution, absorbing refrigerant vapor due to said reduced temperature and evaporating liquid refrigerant due to reduced pressure resulting from said absorption. 85
- 20 23. That improvement in the art of refrigeration which comprises heating an absorbent having refrigerant absorbed therein to expel refrigerant vapor therefrom, reducing the temperature of said vapor in order to liquefy it, passing the liquefied refrigerant to an evaporator, preventing the condensation of vaporous refrigerant in said evaporator by maintaining the partial pressure of the refrigerant comparatively low due to the presence of an inert gas in the evaporator, reducing the pressure and temperature of said absorbent, absorbing refrigerant vapor due to said reduced temperature and evaporating liquid refrigerant due to reduced pressure resulting from said absorption. 90
- 25 24. A refrigerating system comprising generating, absorbing, condensing and evaporating means connected to form a system, said system containing a solid absorbent, a refrigerant, and an auxiliary fluid of less specific weight than the refrigerant and non-absorbable in the absorbent. 95
- 30 25. A refrigerating system comprising gen- 100
- 35 erating, absorbing, condensing and evaporating means connected to form a system, said system containing a solid absorbent, a refrigerant and a fluid inert with respect to the refrigerant and non-absorbable in the absorbent, and means to heat and cool the system to cause the inert fluid to flow into and out of the absorber. 105
- 40 26. A refrigerating system comprising generating, absorbing, condensing and evaporating means connected to form a system, said system containing a solid absorbent, a refrigerant and a fluid inert with respect to the refrigerant and non-absorbable in the absorbent, and means to heat and cool the system to cause the inert fluid to flow between the absorber and the evaporator. 110
- 45 27. A refrigerating apparatus comprising a generator-absorber containing a solid absorbent and a refrigerant, an evaporator in heat exchange relation with the objective of refrigeration, a collecting vessel substantially insulated from the objective of refrigeration and situated above the evaporator, said collecting vessel containing a fluid of less specific gravity than the refrigerant and non-absorbable in the absorbent, a condenser, and conduits connecting the aforementioned parts to form a system. 115
- 50 28. A refrigerating apparatus comprising a generator-absorber containing a solid absorbent comprising calcium chloride and containing ammonia, an evaporator in heat exchange relation with the objective of refrigeration, a collecting vessel substantially insulated from the objective of refrigeration and situated above the evaporator, said collecting vessel containing hydrogen, a condenser, and conduits connecting the aforementioned parts to form a system. 120
- 55 29. That improvement in intermittent type refrigeration which consists in maintaining the space above liquid refrigerant in the evaporator always filled with an additional fluid lighter than the refrigerant for preventing condensation in the evaporator. 125
- 60 30. That improvement in intermittent type refrigeration which consists in maintaining the space above liquid refrigerant in the evaporator always filled with an additional fluid lighter than the refrigerant for preventing condensation in the evaporator and providing a collecting space for the additional fluid above the evaporator to take care of variations in quantity of liquid refrigerant in the evaporator. 130
